[57] **CLAIM**

The ornamental design for a portable emergency alarm
transmitter, as shown.

DESCRIPTION

FIG. 1 is a perspective view of a portable emergency
alarm transmitter showing my new design;

FIG. 2 is a top plan view thereof;

FIG. 3 is a bottom plan view thereof;

FIG. 4 is a side elevational view taken from the right of
FIG. 1, the opposite side being a mirror image thereof;

FIG. 5 is a front elevational view, the rear elevational
view being a mirror image thereof.

FIG. 1

FIG. 2

FIG. 3

FIG. 4

FIG. 5
